UNITED STATES PATENT OFFICE.

CHARLES ERNEST JONES, OF CHICAGO, ILLINOIS.

DESIGN FOR A CLAMP FOR LIGHT-REFLECTING BOWLS.

50,814.

Specification for Design.

Patented May 22, 1917.

Application filed February 26, 1917. Serial No. 151,131. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for a Clamp for Light-Reflecting Bowls, of which the following is a specification, reference

being had to the accompanying drawing, forming a part thereof, wherein the figure is a perspective view of a clamp for light-reflecting bowls, showing my new design.

I claim as my invention:

The ornamental design for a clamp for light reflecting bowls, as shown.

CHARLES ERNEST JONES.
